UNITED STATES PATENT OFFICE.

DAVID YOUNG TOMLINSON, OF ROSWELL, NEW MEXICO.

MOLD.

1,115,618.

Specification of Letters Patent.

Patented Nov. 3, 1914.

Application filed February 21, 1913. Serial No. 749,957.

To all whom it may concern:

Be it known that I, DAVID Y. TOMLINSON, a citizen of the United States, residing at Roswell, in the county of Chaves and State 5 of New Mexico, have invented certain new and useful Improvements in Molds, of which the following is a specification, reference being had therein to the accompanying drawing.

10 This invention relates to a mold for forming a plastic stave which is to be used in building silos and other similar structures.

One of the objects is to provide a mold 15 which may be easily set up and which may be securely held in a set up position while in use.

Another object of the invention is to provide a mold which is so constructed that 20 the various parts may be easily taken to pieces, thus permitting them to be put away in a small amount of space when the mold is not in use.

Another object of the invention is to provide 25 a mold which will cause the stave to be provided with edge grooves, thus forming pockets in which mortar may flow to hold the staves together.

With these and other objects in view this 30 invention consists of certain novel combinations, constructions, and arrangements of parts as will be hereinafter fully described and claimed.

In the accompanying drawings:—Figure 35 1 is a top plan view of the mold. Fig. 2 is an end elevation of the mold. Fig. 3 is a sectional view through the mold along the line 3—3, in Fig. 1. Fig. 4 is a sectional view along the line 4—4, in Fig. 1. Fig. 5 40 is a fragmentary perspective view of one end portion of the mold. Fig. 6 is a perspective view of the flooring strip of one of the mold sections. Fig. 7 is a perspective view of one of the end strips of one of the 45 mold sections. Fig. 8 is a bottom plan view of two of the staves showing the manner in which they fit together. Fig. 9 is a perspective view of the staves shown in Fig. 8.

This invention comprises a base having 50 the longitudinally extending side strips 10 and the transversely extending cross bars 11 which connect the side bars 10 and form the principal supporting means for the upper portion of the mold. These cross bars 55 carry the longitudinally extending beams 12 which have their ends connected by the

bolts 13. Vertical standards 14 are provided with reduced lower end portions 14' extending into the space between the beams 10 and 12 and are secured to the beam 10 by 60 any suitable means. The upper ends of these standards 14 are connected with a longitudinally extending upper beam 15, which beam is connected with a second longitudinally extending beam 16 by means of the 65 bolts 17. Notches 18 are formed in the end portions of the upper and lower beams 12, 15 and 16 and a wedge shape block 19 is rigidly secured in the outer end portions of each of these notches so that when the securing wedges 20 are driven into place they 70 will force the angle bars 21 toward the centers of these longitudinally extending beams, thus compressing the mold sections and holding them in the desired position. 75 This portion of the mold constitutes the frame in which the strips forming the mold sections are placed, and it will be readily seen that when these mold sections are in place that tightening the wedges 20 will 80 cause the sections to be held in the desired position. Each of these sections comprises the bottom strip 22 which rests upon the cross bars 11 and which are provided with a groove 23 forming a bead 24 on the lower 85 edge of the stave 25. The end strips 26 rest upon the bottom strips 22 and are each provided with a bead 27 forming a groove 28 in the side edge of the stave. The edge portions of the strips 22 and 26 are provided 90 with cut-out portions forming seats 29 in which the ends of the side strips 30 fit as clearly shown in Fig. 1. It should be noted that these end strips 26 are so formed that the edges of the staves will be formed at an 95 angle, thus causing the staves to readily go together to form a circular silo. When setting up this mold the sections are placed in the mold as shown in Fig. 1 and with vertical angle irons 31 placed between the side 100 strips 30 of the sections and with transversely extending angle irons 32 between the end strips of the sections. The vertical angle irons rest upon the transversely extending bars 11 and the transversely extending angle irons 32 rest upon the longitudinally extending bars 12 and upper longitudinally extending bars 15 and 16. After the mold sections have been set up the wedges 105 20 are driven until wedged tightly into 110 place, and the bolts 13 and 17 are then tightened and the mold is ready for use.

A suitable mixture of cement or any other desired plastic is poured into the mold sections and is allowed to remain until hardened after which the wedges are removed 5 and the bolts 13 and 17 loosened to permit the sections of the mold to be removed and the cement staves carried to a suitable storage place. The staves which are formed in this mold are set up as shown in Fig. 9 10 with the grooves 28 registering, thus forming pockets in which the mortar will harden and form locking pins holding the staves together. When this device is no longer to be used the various parts may be disconnected 15 and the entire device can then be very easily packed away in a small amount of space. If it is desired to form additional staves after removing those already formed the sections can again be set up after which 20 the mold will be again filled with the plastic mixture and the operation repeated.

Top strips 33 are provided for the mold sections and are provided with beads 34 forming grooves 35 in the upper edges of 25 the staves 25. The tongues 24 fit into these grooves and hold the staves in the desired position.

It should be understood that the standards 14 will constitute an abutment on the 20 rear side of the mold against which the beams 12 and 15 may rest when setting the mold up for operation. It should be understood, however, that it is not necessary that standards similar to the standards 14 be em-

ployed upon the front side of the mold, for 35 the reason that an abutment is not necessary on the front side of the mold, and further for the reason that one side of the mold is adapted to be open when setting up or taking down the mold. 40

Having thus described the invention what is claimed as new, is:—

A mold comprising a base, a plurality of side members, end members carried by said side members, a plurality of series of block 45 molds, bars interposed between said series and extending transversely of said mold, transversely extending rods carried by the ends of said side bars, nuts threaded upon said transversely extending rods for tightening the same and causing said side members to be slightly compressed, end members carried by said side members, coöperating wedges, said side members provided with notched portions formed therein, said 55 wedges fitting in said notched portions, and said wedges adapted to compress said end members toward each other for taking up the shrinkage of the material out of which the mold is formed due to the expansion 60 and contraction of said material.

In testimony whereof I hereunto affix my signature in presence of two witnesses.

DAVID YOUNG TOMLINSON.
